UNITED STATES PATENT OFFICE.

JOHN A. BENGTSON, OF CROMPTON, RHODE ISLAND.

MORTISE-GAGE.

SPECIFICATION forming part of Letters Patent No. 724,077, dated March 31, 1903.

Application filed October 16, 1902. Serial No. 127,612. (No model.)

To all whom it may concern:

Be it known that I, JOHN A. BENGTSON, a citizen of the United States, residing at Crompton, in the county of Kent and State of Rhode Island, have invented a new and useful Improvement in Mortise-Gages, of which the following is a specification.

This invention has reference to an improvement in a mortise-and-tenon gage; and it consists in the peculiar and novel construction of the gage, as will be more fully set forth hereinafter.

The object of the invention is to construct a graduated mortise-and-tenon gage so that the two sliding parts of the gage may be independently adjusted and secured in the adjusted position by one clamp-screw and marking-disks rotatably supported on the sliding rods.

Figure 1 is a side view of my improved mortise-gage, showing the same adjusted to mark a tenon or mortise one inch from the end of the gage-block. Fig. 2 is a longitudinal sectional view of the same. Fig. 3 is a top view, partly in section, showing the gage in the closed position in solid lines and the width-gage extended beyond the face of the gage-block in broken lines. Fig. 4 is a transverse sectional view showing the two gage- rods clamped by the said screw.

In the drawings, *a* indicates the gage-block, which is provided with a cylindrical bore *a'* and has the flanged end *a²*, projecting, preferably, in all directions beyond the gage-block *a* and forming the contact-face *a³*. In the contact-face *a³* the cavity *a⁴* is formed, and in the gage-block *a* the thumb-screw *a⁵* extends radially from the center of the cylindrical bore *a'*. In the bore *a'* of the gage-block the slotted tube *b* is supported, so as to slide freely longitudinally. Within the slotted tube *b* is supported the cylindrical rod *c*. The thumb-screw *a⁵* is in screw-thread engagement with the gage-block and has at its inner end the cylindrical projection *a⁶*, which extends through the slot *b'* in the tube *b*, so that the end of the thumb-screw can bear on the cylindrical rod *c* and force the same against the wall of the slotted tube *b* and

clamp this tube *b* against the wall of the cylindrical bore *a'* in the gage-block. The rotatable marking-disk *b²* is provided with a tubular projection *b³*, which enters a socket *b⁴* in the end of the tube *b*. The tubular projection *b³* is provided with a peripheral groove 55 into which the pin *b⁵* enters. The marking-disk *b²* may therefore revolve freely and is held against longitudinal movement by the pin *b⁵*. The marking-disk *c'* is rotatably supported on the end of the cylindrical rod *c* by 60 means of the screw-post *c²*, secured by screw-thread engagement in the end of the cylindrical rod. The cylindrical rod *c* is graduated from the marking edge of the marking-disk *c'*, which forms the zero of the graduation. The slotted tube *b* is graduated from the marking edge of the marking-disk *b²*, the marking edge of the disk forming the zero of the graduation. The gage may be used as a width-gage by adjusting the slotted tube so that the 70 rotatable marking-disk *b²* is contained within the cavity *a⁴* in the gage-block *a*.

Having thus described my invention, I claim as new and desire to secure by Letters Patent—

1. In a mortise-gage, the combination with a gage-block having a cylindrical bore, a slotted tube and a rotatable marking-disk mounted in the end of the tube, of a cylindrical graduated rod supported in the slotted tube, 80 a rotatable marking-disk supported in the end of the tube, and a clamping-screw adapted to bear on the cylindrical rod, whereby the slotted tube and rod are held in a predetermined position, as described. 85

2. In a mortise-gage, a gage-block, a cavity in the face of the gage-block, a graduated longitudinally-slotted tube, in combination with a cylindrical graduated rod and rotatable marking-disks mounted on the ends of 90 the slotted tube and the cylindrical rod, and means comprising a thumb-screw whereby the slotted tube and graduated rod are held in a predetermined position, as described.

3. In a mortise-gage, the combination with 95 the gage-block *a*, the cylindrical bore *a'* in the gage-block, the cavity *a⁴*, the flange *a²* and the thumb-screw *a⁵*, of the graduated and

longitudinally-slotted tube b , the rotatable marking-disk b^2 , the tubular projection b^3 on the marking-disk, a peripheral groove on the projection b^3 , the pin b^5 , the graduated rod c and the rotatable marking-disk c' supported on the end of the rod c , as described.

In testimony whereof I have signed my

name to this specification in the presence of two subscribing witnesses.

JOHN A. BENGTSON.
